DESIGN FOR A MALLET

George Pavlinetz, Carteret, N. J.

Application December 11, 1947, Serial No. 143,099

Term of patent 3½ years

(Cl. D93—4)

To all whom it may concern:

Be it known that I, George Pavlinetz, a citizen of the United States of America, residing at Carteret, in the county of Middlesex, State of New Jersey, have invented a new, original, and ornamental Design for a Mallet, of which the following is a specification, reference being had to the accompanying drawing, forming part thereof.

Figure 1 is a front elevation, Figure 2 the handle end view, Figure 3 a side elevation and Figure 4 the head-end view of a mallet showing my new design.

I claim:

The ornamental design for a mallet, as shown.

GEORGE PAVLINETZ.
